UNITED STATES PATENT OFFICE.

WILLIAM M. SCOTT, OF PHILADELPHIA, PENNSYLVANIA, ASSIGNOR TO CUTTER ELECTRICAL & MANUFACTURING COMPANY, A CORPORATION OF NEW JERSEY.

AUTOMATIC MAGNETIC CIRCUIT-BREAKER.

SPECIFICATION forming part of Letters Patent No. 758,938, dated May 3, 1904.

Application filed July 31, 1903. Serial No. 167,719. (No model.)

To all whom it may concern:

Be it known that I, WILLIAM M. SCOTT, a citizen of the United States, residing at Philadelphia, in the county of Philadelphia and State 5 of Pennsylvania, have invented a new and useful Automatic Magnetic Circuit-Breaker, of which the following is a specification.

My invention relates to electric switches, more particularly those of the automatic type 10 which operate to disrupt or change the condition of a circuit upon the occurrence of predetermined conditions.

My invention comprises an automatic magnetic circuit-breaker whose function is to disrupt or change the condition of a circuit upon 15 the occurrence in such circuit or any other circuit of an abnormal current flow or when the current-flow is for any reason reversed. It is an automatic magnetic circuit-breaker designed to disrupt a circuit when the current in such circuit attains a predetermined value and to interrupt such circuit also in case the direction of the current or energy flow is reversed.

25 My invention comprises an automatic magnetic circuit-breaker designed to interrupt a circuit carrying electric currents of great magnitude when such currents attain a predetermined value and also to interrupt such circuit 30 when the current attains a relatively small value when flowing in a reversed direction from normal.

My invention comprises tripping mechanism for automatic magnetic switches, such 35 tripping mechanism being simple in structure, efficient in operation, and compactly arranged and operating to actuate or control the switch or circuit-breaker upon the occurrence of an abnormal current-flow or energy-flow in either 40 direction and also upon the reversal of the current or energy flow—that is, in a direction opposite to normal.

The automatic circuit-breaker hereinafter 45 described serves equally well for the protection of circuits or apparatus carrying or supplied with continuous, fluctuating, or alternating current.

Reference is to be had to the accompanying drawings, in which—

Figure 1 is a front view in elevation of a 50 switch or circuit-breaker embodying my invention. Fig. 2 is a side view, partly in section, of the circuit-breaker shown in Fig. 1. Fig. 3 is a fragmentary view showing the disposition and arrangement of the tripping-coils 55 and their cores. Fig. 4 is a plan view, on reduced scale, of the magnetic circuit of the core and adjusting device of the potential or shunt coil. Fig. 5 is a diagram of the circuits through the switch and coils. 60

At 1 is shown a base or switchboard, of insulating material, upon which are mounted the main contact blocks or terminals 2 and 3, composed of blocks of copper secured to the base 1, one vertically above the other, and having 65 their contact or engaging faces in approximately the same vertical plane. These blocks 2 and 3 are secured to the base by means of studs or bolts extending through the base from the rear and engaging the blocks 2 and 3 70 by screw-threads. These studs or bolts serve also as circuit connections. The stud 4 secures the terminal-block 2, while the stud 5 secures the terminal-block 3. 75

6 is a laminated bridging member, the beveled ends of the laminae of which engage the terminal-blocks 2 and 3, thus permitting the passage of current from one of these terminal blocks to the other. The laminated bridging member 6 is secured to but insulated from 80 the arm 7, pivoted in the frame 8 at 9. Integral with the arm 7 and forming an upward extension thereof is the portion 10, serving to support the metallic and carbon movable shunt contact-pieces. The movable metallic 85 shunt contact-piece is shown at 11 as carried by the spring members 12, secured to but insulated from the extension 10.

13 is a stop which prevents the contact-piece 11 from extending forward beyond a 90 certain desired position and insures the separation of the metallic shunt contact-pieces prior to the separation of the carbon shunt contact-pieces.

14 is a metallic member secured to but insulated from the extension 10 and carries at its upper end the pivot 15, about which rotates the frame 16, carrying the movable shunt 5 carbon piece 17. The pivotal motion of the carbon 17 is controlled by the spring 18.

Mounted directly upon and above the main contact-block 2 is the bracket 19, of metal, carrying near its lower end the metallic plate 10 20, serving as the stationary metallic shunt contact-piece and co-operating with the contact-piece 11. At the upper end of the bracket 19 is the pivot 21, about which revolves the bracket 22, which carries the stationary shunt 15 carbon piece 23. The pivotal motion of carbon 23 is controlled by spring 24.

As a convenient means for bringing all of the aforementioned contacts into engagement and circuit-closing position there is provided 20 an operator's handle 25, mounted in the outer end of the lever member 26, which is pivoted to the frame 8 at 27. The lever member 26 extends beyond the pivot 27 by the portion 28 integral with it. At the extremity of extension or portion 28 is a pivot 29, and between this pivot and the pivot 30 in the member 7 extends the link 31. The link 31 and extension 25 28 form a toggle for cramping the laminated bridging member 6 into firm engagement with the contact-blocks 2 and 3, as well understood in the art.

32 is a lug or projection extending from and integral with the lever member 26 and carries the pivot 33 for a small roller adapted to be engaged by the hooked portion 34 of the lever 35, pivoted to the frame 8 at 36. With the parts in the position shown in Fig. 2 the lever 35 operates as a latch to restrain the spiral springs 37 and 38 from opening the circuit-breaker. Spiral spring 37 is connected between the pin 39 on the arm 7 and the pin 40 on the frame 8. The spiral spring 38 extends between the pin 41 on extension 28 and the pin 40. The lever 35 has also a projection 45 42, having a surface adapted to engage the roller mounted upon the pin 33, so that when the lever member 35 rotates in a clockwise direction about its pivot 36, as viewed in Fig. 2, the lever member 26 is forced outwardly by 50 the lever member 35 striking a blow.

Extending toward the base 1 and beyond the pivot 36 is the portion 43 integral with the lever member 35. Pivoted at 44 at the outer end of extension 43 is the vertically-disposed 55 rod 45, carrying the pin, extending transversely and horizontally through it, (shown at 46.) Any force, therefore, having a vertical component and applied to the rod 45 or the pin 46 will, if of sufficient magnitude, cause 60 the latch 34 to release the lever member 26, thus causing the circuit-breaker to open. Means for applying such force are in this case tripping-coils and their armatures, as hereinafter described.

65 47 and 48 are two coils connected in parallel

with each other and in series with the main circuit and composed of a relatively few turns or convolutions of heavy conductor. The axes of these coils are horizontal and approximately parallel with the front surface of the base or 70 switchboard 1. Extending through the coils 47 and 48 are the iron cores 49 and 50, respectively, insulated from such coils and supported by the base 1. The iron core 49 has flattened portions 51 and 52 on the under side 75 of each end. Adapted to approach these flattened portions are the blocks of iron 53, mounted on and secured to the non-magnetic member 54, pivoted at 55 in an extension 56 of a bracket or frame secured to the base 1. 80 Extending beyond the pivot 55 and away from the base 1 are the portions 57 integral with the members 54, the members 57 being connected at their outer ends by a member 58 extending horizontally across in front of the 85 switch.

59 is a lug on the upper side of the extension 57 and adapted to engage the ear or bracket 60, secured to and extending downwardly from the frame 8. This lug 59 prevents by its engagement with ear 60 a rotation of the block of iron or armature 53 in a counter-clockwise direction, as viewed in Fig. 2, beyond a definite position.

The current through the automatic circuit-breaker may be supposed to enter by means of the stud 4, passing to contact-block 2, thence through laminated bridging member 6 to contact-block 3, to stud 5, through the copper link 61 to stud 62, thence through the coils 47 90 and 48 in parallel to the stud 63, and departing from the circuit-breaker by this stud 63. When the current so passing, whether alternating, fluctuating, or continuous, attains a predetermined value, the armatures 53 are 100 attracted upwardly toward the flattened faces 51 and 52 of the core 49. In thus rotating in a clockwise direction about the pivot 55, as viewed in Fig. 2, the vertical rod 45, which is guided through the portion 64, fixed with 110 respect to the base 1, is engaged and forced upwardly, thus causing the latch member 35 to rotate in a clockwise direction about its pivot 36 and trip the circuit-breaker, as heretofore described. This tripping by coil 47 115 and core 49 is independent of the direction of the current-flow or energy-flow in the circuit and is dependent only upon the strength of the current.

At 65 is shown a coil or winding whose axis 120 is horizontal and at an elevation midway between the axes of the cores 49 and 50. The axis of the coil 65 is also approximately parallel with the front face of the base 1. This winding 65 is supported by the base 1 in any 125 suitable manner and surrounds a core 66, extending horizontally through the winding 65, but at all points free from the winding 65 and capable of rotation about its horizontal axis. In the members 60, secured to and ex- 130

tending downwardly from the frame 8, are the two conical pivots 67 concentric with the axis of the winding 65 and the core 66. Secured to each end of the core 66 is a side piece or bar 68, also of iron, extending in a direction approximately at right angles with the front of the base 1 and terminating in pole-pieces 69, arranged between the cores 49 and 50 and coming opposite the flattened portions 70 of the core 49 and flattened portions 71 of core 50. The iron side bars 68 extend away from the base 1 and beyond the pivots 67 and are connected at their outer ends by the horizontally-disposed plate 72. There is thus formed by the core 66 and side bars 68 a pivoted magnetic system whose magnetization is dependent upon the ampere-turns of the coil or winding 65. This magnetic system is capable of rotary motion about the axis of the core 66. The winding 65 is so connected in the electric circuit that the current at any instant passing through such winding will so magnetize the pole-pieces 69 that they will be attracted by the poles of the core 49, if at the same instant the current flow or energy flow through the circuit of the coil 47 is in the normal or desired direction. Ordinarily the winding 65 is connected in shunt to the bus-bars or circuit-conductors, whereas the coils 47 and 48 are connected in series in the circuit. Ordinarily the winding 65 is of high resistance and composed of a relatively great number of turns of relatively fine wire. The terminals of the winding 65 are attached to binding-post 73 and contact-piece 76, respectively. The contact-piece 74 is carried by the laminated bridging member 6. The downwardly-extending electrical connection 75 commutes in the well-known manner with the member 14. The contact-piece 74 is so arranged that it disengages from the spring-pressed contact 76 when the circuit-breaker opens. The screw 77, communicating with binding-post 73, is connected with a bus-bar or circuit-conductor.

The operation of the device is as follows: The current normally passes through the circuit-breaker by the path formerly traced—that is, the coils 47 and 48 are in parallel with each other, but in series with the translating device T in the main circuit. If the current in the circuit attains a predetermined value irrespective of the direction of the current or energy flow, the armature 53 is attracted by core 49, and the circuit-breaker tripped, as heretofore explained. Suppose the energy flow to be of normal direction through the circuit-breaker and the translating device T and that at a given instant the pole of the core 49, as viewed in Fig. 2, is a north pole, due to the direction of winding of the coil 47. The winding of the coil 48 is such that at the same instant the pole of the core 50, as viewed in Fig. 2, is a south pole. The connections or direction of winding of the coil 65 are such

that at the same instant the pole 69, as viewed in Fig. 2, is a south pole. There is then a repulsion of pole 69 by the pole of the core 50 and simultaneously an attraction between the pole 69 and the pole of the core 49. In virtue of these forces the bars 68 tend to rotate in a counter-clockwise direction about the pivots 67, but engage the brass pins 78 in the upper faces of the poles of the core 49. Suppose, however, that the current or energy flow in the circuit is for some reason reversed. In such case the pole 69, due to the method of connection of the winding 65, remains a south pole; but the pole of the core 49 now becomes a south pole and the pole of the core 50 becomes a north pole. In such case the pole of the core 49 repels the pole 69, while the pole of the core 50 attracts the pole 69. In consequence the core 66 and bars 68 rotate in a clockwise direction about the pivots 67, and the lug 79, embracing rod 45 and extending from a tie-bar 80, rises and imparts a blow to the transverse pin 46, causing the latch 35 to rotate in a clockwise direction about its pivot 36, and thus release the lever member 26, causing the circuit-breaker to open. It is thus seen that the circuit-breaker is tripped when the direction of the current or energy flow is reversed and also in case the current or energy flow, irrespective of direction, attains a predetermined value.

The armature 53 may obviously be so arranged with respect to the rod 45 and the core 49 that it will normally be held attracted, and upon the current or energy flow diminishing to a predetermined value the armature will be released, and thus trip the circuit-breaker. The circuit-breaker would then operate on underload as well as upon a reversal of the current or energy flow.

Though the winding 65 has been referred to as connected in shunt across the main-circuit leads or bus-bars, it is to be understood that it may be connected in any other manner whatsoever so long as the current passing through it at any instant is of such direction that if the current-flow or energy-flow in the main circuit at the same instant is in normal or desired direction the circuit-breaker will not be tripped, or the current passing through it at any instant is of such direction that if the current-flow or energy-flow in the main circuit is in reversed or contrary to normal direction the circuit-breaker will be tripped. In fulfilling such conditions the coil 65 may be connected with an entirely separate source of energy from that causing the flow in the circuit to be interrupted or controlled, or in the case of alternating currents the coil 65 may be connected in the secondary circuit of either a step-up or step-down transformer whose primary winding is either directly or indirectly connected with the circuit to be interrupted or controlled, or the winding 65 may be connected in any other manner so long as the fore-

going conditions are fulfilled. It need not to fulfil such conditions in every case be a shunt-winding, potential winding, or fine-wire winding.

5 When employed in connection with an alternating-current circuit, the core 66, as well as cores 49 and 50, are preferably laminated, and a tube, of brass, copper, or other material, may surround the core 66, thus acting 10 as a short-circuited secondary winding of a transformer and operating to reduce the impedance of the coil or winding 65.

In Fig. 4 is shown a plan view of the core 66 and bars 68. One bar, 68, is shorter than 15 the other in the portion extending beyond the pivots 67 in the direction away from the base 1. The connection 72 is slotted horizontally, and through this slot extends a thumb-screw 81, engaging an adjustable weight 82. By 20 sliding the weight 82 along the inclined bar 72 the pivoted magnetic frame, comprising the bars 68 and core 66, may be brought to a condition as near exact balance about the pivots 67 as may be desired. In consequence with 25 the coil 65 furnishing its normal number of ampere-turns a very slight reversed current or reversed energy-flow in the coils 47 and 48 will cause the circuit-breaker to be tripped. The frame comprising bars 57 and 58, supporting the armature 53, is of similar arrangement. The thumb-screw 83 extends through the slot 84 in the bar 58 and supports at any position along the slot 84 the weight 85. Current-graduations are marked on the bar 58, 30 and potential-graduations or any other desired graduations are marked upon the bar 72. Screwing the weights 82 and 85 opposite any graduation-marks will determine under what conditions the circuit-breaker will open.

40 The hereinbefore-described circuit-breaker may be used in connection with storage-battery systems or in connection with rotary converters, both of which are devices capable of causing reversed energy-flow. It may also be used in connection with direct-current or alternating-current circuits in any relation where the reversal of current or reversal of energy-flow may occur—as, for example, where several generators operate in parallel to 45 supply current to bus-bars or feeder-conductors or where a plurality of feeder-circuits communicate between a source and a consumption circuit or apparatus, where a short circuit on one of the several feeder-circuits 50 may cause a reversed energy-flow in that part of the feeder-circuit beyond a short circuit.

Though I have shown my invention embodied in a particular type of electric switch, it is to be understood that it may be used in 60 connection with any type of electric switch, as the tripping mechanism may obviously be applied to any latch or switch restraining means.

Though the coil 65 may be traversed by an 65 alternating current, as heretofore explained,

and in consequence the poles 69 may be constantly changing in polarity, it is nevertheless to be remembered that at any instant of time, whether direct or alternating current be passing through the coil 65, the polarity 70 of the poles 69 is constant or unchanging as regards the polarity of the poles of the cores 49 and 50. For the sake of brevity, therefore, the coil 65 will be referred to in the claims whether such coil carry direct current or alternating current as a coil of constant polarity, and similarly poles 69 and their associated magnetic system applied to the core 66 and bars 68 may be referred to as a member or mass of constant or unvarying polarity. 80

Though I have described the contact-blocks 2 and 3 and the laminated bridging member 6 as in the same circuit with the coils 47 and 48, such coils may be in the circuit separate and independent from the switch-contacts. 85 The coils 47 and 48 may be joined in series with each other in place of in parallel. Furthermore, the cores of the coils 47 and 48 may be in the same magnetic circuit in place of independent. 90

What I claim is—

1. In an automatic electric switch, separable coöperative contacts, means for restraining said contacts in normal position, fixed magnetic cores, exciting-coils therefor, a movable magnetic member, an exciting-coil therefor whose axis approximately coincides with the axis of movement of said magnetic member, said coils being so connected and disposed that upon the occurrence of reversed energy-flow said cores will coöperate to control said restraining means. 95

2. In an automatic electric switch, separable coöperative contacts, means for restraining said contacts in normal position, fixed magnetic cores, exciting-coils therefor, a pivoted magnetic member, an exciting-coil therefor, whose axis approximately coincides with the pivotal axis of said magnetic member, said coils being so connected that the energy-flow through some of them is always in a given direction, and upon a reversed energy-flow through the remainder of said coils, said cores and magnetic member coöperate to control said restraining means. 105 110 115

3. In an automatic electric switch, separable coöperative contacts, means for restraining said contacts in normal position, two magnetic cores, coils for energizing said cores and so disposed as to cause adjacent ends of said cores to be oppositely polarized, a pivoted magnetic member movable relatively to and coöperating with said magnetic cores, a coil for energizing said magnetic member and having its axis approximately coinciding with 120 the pivotal axis of said magnetic member, said cores being so disposed as to coöperate with said magnetic member to control said restraining means upon reversed energy-flow. 125

4. In an automatic electric switch, separable 130

coöperative contacts, means for restraining said contacts in normal position, two independent fixed cores, a coil for exciting each core, a pivoted magnetic member having poles situated between the poles of said independent cores, a coil for energizing said pivoted magnetic member and having its axis approximately coinciding with the pivotal axis of said magnetic member, said coils being so connected that the energy-flow through some of them is always in a given direction, and upon a reversed energy-flow through the remainder of said coils said cores and magnetic member coöperate to control said restraining means.

5. In an automatic electric switch, separable coöperative contacts, means for restraining said contacts in normal position, two independent fixed cores, a current-coil for exciting each core, a pivoted magnetic member having poles situated between the poles of said independent cores, a potential-coil for energizing said magnetic member and having its axis approximately coinciding with the pivotal axis of said magnetic member, said coils being so connected that the energy-flow through some of them is always in a given direction, and upon a reversed energy-flow through the remainder of said coils said cores and magnetic member coöperate to control said restraining means.

6. In an automatic electric switch, separable coöperative contacts, means for restraining said contacts in normal position, a plurality of windings exciting a plurality of fixed cores, a pivoted magnetic member, an exciting-coil therefor having its axis approximately coinciding with the pivotal axis of said magnetic member, said cores and magnetic member coöperating to control said restraining means upon a reversal of energy-flow.

7. In an automatic electric switch, separable coöperative contacts, means for restraining said contacts in normal position, a plurality of current-coils having independent magnetic circuits, means controlled by one of said coils for actuating said restraining means upon the occurrence of predetermined current-flow, a constantly-polarized coil, a magnetic circuit therefor attracted by said current-coil which controls said restraining means upon the occurrence of predetermined current-flow, and repelled by another of said current-coils during the continuance of the energy-flow in normal direction.

8. In an automatic electric switch, separable coöperative contacts, means for restraining said contacts in normal position, a current-coil-controlling means for actuating said restraining means upon the occurrence of predetermined current-flow, a constantly-polarized member attracted by said current-coil during energy-flow in normal direction, and repelled by said current-coil upon the occur-

rence of reversed energy-flow to actuate said restraining means.

9. In an automatic electric switch, separable coöperative contacts, means for restraining said contacts in normal position, a current-coil, a pivoted armature coöperating with said coil to actuate said restraining means upon the occurrence of predetermined current-flow, and a pivoted constantly-polarized member coöperating with said current-coil for actuating said restraining means upon the occurrence of reversed energy-flow.

10. In an automatic electric switch, separable coöperative contacts, means for restraining said contacts in normal position, a plurality of current-coils having independent magnetic circuits, a pivoted armature coöperating with one of said coils to actuate said restraining means upon the occurrence of a predetermined current-flow, and a pivoted constantly-polarized member coöperating with the magnetic circuits of said coils for actuating said restraining means upon reversed energy-flow.

11. In an automatic electric switch, separable coöperative contacts, means for restraining said contacts in normal position, a plurality of current-coils having independent magnetic circuits, means coöperating with one of said coils for actuating said restraining means upon the occurrence of predetermined current-flow, a constantly-polarized coil, a pivoted magnetic circuit therefor coöperating with the magnetic circuits for actuating said restraining means upon reversed energy-flow.

12. In an automatic electric switch, separable coöperative contacts, means for restraining said contacts in normal position, a current-coil coöperating with means for actuating said restraining means upon the occurrence of predetermined current-flow, a constantly-polarized coil, a magnetic circuit therefor a pivotal support for said magnetic circuit, the pivotal axis coinciding approximately with the axis of said coil, said magnetic circuit coöperating with said current-coil to actuate said restraining means upon the occurrence of reversed energy-flow.

13. In an automatic electric switch, separable coöperative contacts, means for restraining said contacts in normal position, a current-coil, a core therefor, means coöperating with said core to actuate said restraining means upon the occurrence of predetermined current-flow, a pivoted magnetic circuit having poles juxtaposed to the poles of the core of said current-coil, means for constantly polarizing said pivoted magnetic circuit, said magnetic circuit and core coöperating to actuate said restraining means upon the occurrence of reversed energy-flow.

14. In an automatic electric switch, separable coöperative contacts, means for restraining said contacts in normal position, a current-coil, a core therefor, a pivoted armature coöperat-

- ing with said core to actuate said restraining means upon the occurrence of predetermined current-flow, a constantly-polarized coil, a magnetic circuit therefor, a pivotal support for said magnetic circuit, the pivotal axis coinciding approximately with the axis of said coil, said core and magnetic circuit coöperating to actuate said restraining means upon the occurrence of reversed energy-flow.
10. 15. In an automatic electric switch, separable coöperative contacts, means for restraining said contacts in normal position, a plurality of current-coils, each having an independent core, a pivoted armature coöperating with one of said cores to actuate said restraining means, a pivoted magnetic circuit having poles arranged approximately the poles of said cores, means for constantly polarizing said pivoted magnetic circuit, said magnetic circuit and cores coöperating to actuate said restraining means.
16. In an automatic magnetic circuit-breaker, a base, contact-blocks mounted thereon, one vertically above the other, a laminated bridging member for engaging said contact-blocks, a toggle for operating said laminated bridging member, a latch for restraining said toggle in extended position, a current-coil, an armature coöperating therewith for actuating said latch, a constantly-polarized magnetic circuit for actuating said latch said magnetic circuit and current-coil coöperating in said latch actuation upon the occurrence of reversed energy-flow.
17. In an automatic magnetic circuit-breaker, a base, contact-blocks located thereon one vertically above the other, a laminated bridging member for engaging said contact-blocks, said contact-blocks and laminated bridging member constituting the main switch, a supplemental switch in shunt to the main switch and comprising fixed and movable metallic shunt contact-pieces, and a member between the base and the support of the movable metallic shunt contact-piece as means for limiting the advance of the movable metallic shunt contact-piece when out of engagement with its coöperating fixed contact, and automatic magnetic means for releasing the main switch.
18. In a tripping mechanism for electric switches, a plurality of independent fixed cores, an exciting-coil for each core, a pivoted magnetic member, a coil for constantly polarizing said magnetic member and having its axis approximately coincident with the pivotal axis of said magnetic member, said cores and magnetic member coöperating for tripping action upon reversed energy-flow through the coils which excite the fixed cores.
19. In a tripping mechanism for electric switches, a latch, a vertically-extending member engaging said latch a pivoted frame approximately balanced, a magnetic mass carried thereby, and oppositely-disposed magnetiz-
- ing-coils coöperating with said mass to actuate said vertically-extending member.
20. In a tripping mechanism for electric switches, a latch member provided with means to impart a blow, a switch member restrained thereby, a pivoted frame approximately balanced, a magnetizable mass supported thereby, and a magnetizing-coil coöperating with said mass to impart a blow through said latch member to said switch member.
21. In a tripping mechanism for electric switches, a latch, a pivoted frame, a magnetizable mass supported thereby, a fixed magnetizing-coil embracing a portion of said frame, the pivotal axis of said frame coinciding approximately with the axis of said magnetizing-coil, and a magnetizable mass coöperating with said pivoted frame for actuating said latch.
22. In a tripping mechanism for electric switches, a latch, a pivoted frame, a magnetizable mass supported thereby, a fixed magnetizing-coil embracing a portion of said frame, the pivotal axis of said frame coinciding approximately with the axis of said magnetizing-coil, and a magnetizable mass coöperating with said pivoted frame for delivering a blow to said latch.
23. In a tripping mechanism for electric switches, a latch, a horizontally-disposed pivoted frame, a magnetizable mass supported thereby and a magnetizing-coil, having its axis approximately coincident with the pivotal axis of the frame, coöperating with said magnetizable mass for actuating said latch.
24. In a tripping mechanism for electric switches, a latch, a horizontally-disposed pivoted frame, a magnetizable mass supported thereby and a magnetizing-coil, the axis of which coincides approximately with the axis of said pivot coöperating with said magnetizable mass for delivering a blow to said latch.
25. In a tripping mechanism for electric switches, a latch, a horizontally-disposed pivoted frame comprising a magnetizable mass, a magnetizable core included in said frame, a fixed magnetizing-coil surrounding said core, the pivotal axis of said frame coinciding approximately with the axis of said core and said coil, and a magnetizable mass coöperating with said pivoted frame for controlling said latch.
26. In a tripping mechanism for electric switches, a latch, a horizontally-disposed frame comprising magnetizable material and rotatable about an approximately horizontal axis, a second horizontally-disposed pivoted frame, a magnetizable mass carried thereby, a magnetizing-coil coöperating with said magnetizable mass for actuating said latch, and coöperating with the first-mentioned pivoted frame for actuating said latch.
27. In a tripping mechanism for electric switches, a latch, horizontally-disposed current-coils having independent magnetic circuits, a horizontally-disposed pivoted frame

comprising a constantly-magnetized mass and coöperating with said current-coils for actuating said latch, a second horizontally-disposed pivoted frame, a magnetizing mass carried thereby, a current-coil and said magnetized mass coöperating to actuate said latch.

28. In a tripping mechanism for electric switches, a latch, a plurality of current-coils having independent magnetic circuits, a horizontally-disposed pivoted magnetic frame having its poles approximate the magnetic circuits of said coils, a fixed coil for magnetizing said pivotal magnetic frame said current-coils and magnetic frame coöperating to actuate said latch.

29. In a tripping mechanism for electric switches, a latch, a pivotal support therefor, a vertically-extended member pivoted thereto, a plurality of independent horizontally-disposed pivoted frames, and means coöperating with each frame to actuate said vertically-extending member.

30. In a tripping mechanism for electric switches, a latch, a pivotal support therefor, a vertically-extended member pivoted thereto, a plurality of independent horizontally-disposed pivoted frames, and means coöperating with each frame to deliver a blow to said vertically-extending member.

31. In an automatic electric switch, separable coöperative contacts, means for restrain-

ing said contacts in normal position, two independent fixed cores, a coil for energizing each core in such manner that adjacent poles of said cores shall be of opposite kinds, a pivoted magnetic member, a coil for energizing said pivoted magnetic member and having its axis approximately coinciding with the pivotal axis of said magnetic member, said cores and magnetic member coöperating with each other to control said restraining means upon the relation of the energy-flow in the coils becoming relatively reversed.

32. In a tripping mechanism for electric switches, a plurality of independent fixed cores, a current-coil for exciting each core, a pivoted magnetic member, a potential coil for constantly polarizing said magnetic member and having its axis approximately coincident with the pivotal axis of said magnetic member, said cores and magnetic member coöperating for tripping action upon reversed energy-flow through the coils which excite the fixed cores.

In testimony whereof I have hereunto set my hand and affixed my signature in the presence of two subscribing witnesses.

WM. M. SCOTT.
